INDIANA, ASSIGNEES TO INDIANA BOX COMPANY, OF ELWOOD, INDIANA

PACKING COLLAR

Application filed April 18, 1931. Serial No. 531,132.

This invention relates to a packing collar, particularly adapted for use in connection with the packing or crating of phonograph cabinets and other articles of furniture.

The object of the invention is to provide a collar for surrounding the cabinet or article of furniture to be packed which will securely embrace the same and maintain it in spaced relation with respect to the walls of the crate or packing box to protect it therefrom, permit it to be nailed or otherwise secured thereto so as to hold the cabinet firmly in place, and permit of ready assembling and mounting for convenient and rapid operation.

The particular feature of the invention resides in providing rigid corner pieces for engagement with the corners of the cabinet and for receiving nails through the packing box or crate, said rigid corner members being resiliently connected by a flexible strip so that the entire collar may be flexed for insertion about the cabinet, and the free ends of the resilient strips forming the collar conveniently secured together for holding the collar in place.

The full nature of the invention will be understood from the accompanying drawings and the following description and claims.

Fig. 1 is a perspective view illustrating one position of the collar surrounding a cabinet mounted in a crate. Fig. 2 is a plan view of the cabinet showing the collar sprung in position to be mounted thereabout. Fig. 3 is the same as Fig. 2 showing the collar mounted about the cabinet and secured in place. Fig. 4 is an enlarged front elevation of the connected free ends of the collar. Fig. 5 is a central vertical section through the connected ends illustrated in Fig. 4.

In the drawings, there is shown a packing box 10 in which there is mounted a cabinet 11, similar article, or piece of furniture to be packed for shipment therein. For convenience of description, the article to be packed

is termed a cabinet and the packing case therefor is termed a crate.

For supporting the cabinet within the crate and holding it in spaced relation thereto for preventing scratching or damaging of the usual highly finished exterior, there is provided one or more packing collars surrounding the cabinet in one or more planes of its length. These packing collars are preferably made of wood so that the crate can be nailed thereto and thereby anchor the cabinet in position.

As shown herein, the collar comprises relatively thick and rigid end pieces 12 made of wood to which the crate can be nailed by the nails 13. The ends of the rigid end pieces 12 are connected together through the medium of the nails 14 by the flexible strips 15 at the back thereof and the short flexible strips 16 and 17 having overlapping free ends, at the front thereof. Adjacent the end pieces 12 and secured in position by the flexible strips, there are corner blocks 18 secured to the flexible strips by the nails 19, said blocks thus forming with the end pieces 12, substantially rigid cabinet supporting corners. If desired, felt cushions 20 or other material may be secured in said corners for direct engagement with the corners of the cabinet for further protecting the same.

The overlapping free ends of the strips 16 and 17 may be secured together in any suitable manner after the collar has been mounted about the cabinet through the medium of the staples 21, or any similar securing medium such as tie cords, adhesive wrapping, glue or the like.

By means of the above arrangement, the collar may be built up complete prior to its application to the cabinet and in applying the same, it may be sprung to the position shown in Fig. 2 by reason of the flexible strips whereby it may be readily mounted over the top of the cabinet or about the sides thereof. The free ends of the strips 16 and

17 normally lie in adjacent overlapping position after the collar has been mounted in place and has resumed its normal shape, whereupon the overlapping free ends may 5 be readily secured together by one or more staples as illustrated herein or any other suitable securing means as above suggested. The flexible strips may be of thin ply wood or any other flexible material such as metal, 10 fabric or the like.

The invention claimed is:

1. The combination with an article of merchandise and a packing case therefor, of a packing collar adapted to be secured about 15 said article for maintaining it in fixed spaced relation with respect to said packing case, said collar being formed of rigid and relatively thick end members adapted to bear against said article and anchor it in spaced 20 relation to the packing case, a flexible strip permanently connecting said end members on one side thereof while permitting them to flex away from each other for mounting the same about said article, and means for connecting the said end members on the other side thereof after said collar is mounted in 25 position.

2. The combination with an article of merchandise and a packing case therefor, of a packing collar adapted to be secured about 30 said article for maintaining it in fixed spaced relation with respect to said packing case, said collar being formed of rigid and relatively thick end members adapted to bear 35 against said article and anchor it in spaced relation to the packing case, a flexible strip permanently connecting said end members on one side thereof while permitting them to flex away from each other for mounting the 40 same about said article, and a flexible strip for connecting the other side of the end members after the collar is mounted in position.

3. The combination with an article of merchandise and a packing case therefor, of a packing collar adapted to be secured about 45 said article for maintaining it in fixed spaced relation to said packing case, said collar being formed of rigid and relatively thick end members adapted to bear against said article, 50 a flexible strip permanently connecting said end members on one side thereof while permitting them to flex away from each other for mounting the same about said article, a pair of flexible strips rigidly secured to said 55 end members and having adjacent free ends, and means for securing the adjacent free ends together for holding the collar in position after mounting the same about said article.

60 4. The combination with an article of merchandise and a packing case therefor, of a packing collar adapted to be secured about said article for maintaining it in fixed spaced relation to said packing case, said collar comprising a pair of relatively thick rigid end 65

pieces to which said packing case is adapted to be secured, relatively thick rigid corner blocks mounted adjacent the ends thereof, a flexible strip rigidly secured to the corresponding ends of said end pieces and the adjacent corner blocks, a pair of flexible strips secured to the other corresponding ends of said end pieces and the adjacent corner blocks, said last mentioned strips having free adjacent ends, and means for securing said ends in position for holding said collar about the article after having been sprung into embracing position.

In witness whereof, we have hereunto affixed our signatures.

JOHN W. McILWRAITH.
DENNIS I. MCKENZIE.
